UNITED STATES PATENT OFFICE.

HUGH W. KIMES, OF DAYTON, OHIO, ASSIGNOR TO THE STILWELL-BIERCE & SMITH-VAILE COMPANY, OF SAME PLACE.

DESIGN FOR A DOUBLE-ACTING TRIPLEX-PUMP HOUSING.

SPECIFICATION forming part of Design No. 30,636, dated April 25, 1899.

Application filed March 27, 1899. Serial No. 710,714. Term of patent 14 years.

To all whom it may concern:

Be it known that I, HUGH W. KIMES, a citizen of the United States, residing at Dayton, in the county of Montgomery and State of Ohio, 5 have invented and produced a new and original Design for a Double-Acting Triplex-Pump Housing; and I do declare the following to be a full, clear, and exact description of the same, reference being had to the accompanying drawings, forming a part thereof.

Figure 1 is a side elevation of a housing for a double-acting triplex pump made in accordance with my design. Fig. 2 is an end elevation of the same.

15 The side and end opposite those shown in the drawings are identically the same as those appearing in said drawings. Therefore it will be understood that the said drawings are ample illustrations of the design.

20 As shown in said drawings, the leading or material features of my design comprise four upright standards of uniform height, each of which has a journal-box on its upper end, the said standards being joined near their longitudinal centers by a row of panels and transversely-disposed valve-chambers placed in the space below said panels and connected by suction and discharge pipes.

More particularly describing the essential 30 features of my design, A designates four standards inclining upwardly on both sides from bottom to top and united to a hollow base B. Each of said standards has a journal-box C

on its upper end, and the said standards are all joined together by a line of panels D. The 35 said standards have openings J, J', and J''. (Shown in the end elevation, Fig. 2.) Below the panels D and between the lower ends of the standards there are placed in transverse positions a series of valve-chambers E, having 40 their outer sides closed by bonnets E'. The said valve-chambers E are supported on and communicate with the interior of the base B.

F designates suction-pipes communicating 45 with the ends of the base B and terminating in flanges F'.

H designates discharge-pipes lying along the top of said valve-chambers on each side 50 of the standards. The portions of said pipes adjacent to the upper ends of said valve-chambers are provided with domes H', which 55 inclose the tops of said valve-chambers. The ends of said discharge-pipes terminate in flanges I.

Having described my invention, I claim—
The design for a double-acting triplex-pump 55 housing herein shown and described.

In testimony that I claim the foregoing as my own I hereto affix my signature in presence of two witnesses.

HUGH W. KIMES.

Witnesses:

R. J. McCARTY,
C. NOEL.
